UNITED STATES PATENT OFFICE.

ANDREW J. SANFORD, OF NEWARK, OHIO, ASSIGNOR TO A. H. HEISEY & CO., INC., OF NEWARK, OHIO, A CORPORATION OF WEST VIRGINIA.

DESIGN FOR A MOLASSES-PITCHER.

40,600.

Specification for Design.

Patented Apr. 5, 1910.

Application filed February 2, 1910. Serial No. 541,648. Term of patent 14 years.

To all whom it may concern:

Be it known that I, ANDREW J. SANFORD, a citizen of the United States, residing at Newark, county of Licking, and State of Ohio, have invented a new, original, and ornamental Design for Molasses-Pitchers, of which the following is a specification, reference being had to the accompanying drawing, forming a part thereof.

The drawing is a perspective view of a pitcher showing my new design.

The leading features of my design comprise a pitcher or jug of glass or like mate-

rial of elongated, upwardly tapering shape and provided with vertically extending flat prisms, and having above the prisms a metallic band fitting around the jug and a flat cover body with a lid provided with a knob.

I claim:

The ornamental design for a molasses pitcher, as shown and described.
